SHAPING MACHINE FOR SOLE-SHAPED SHOE PARTS

Walter P. Osgood, Malden, Mass.

Application January 27, 1937, Serial No. 122,559

7 Claims. (Cl. 12—21)

The present invention relates to machines which are used in the manufacture of shoes to shape a sole-shaped shoe part. For purposes of disclosure the various features of the present invention are illustrated as embodied in a machine for shaping a sock lining but it will be apparent to those skilled in the art that certain features of the present invention may be used advantageously in a machine for shaping other sole-shaped shoe parts such, for instance, as soles.

In the manufacture of shoes of the arch support type, the building in of the arch support necessitates changes in the form of the insole. Usually this change takes the form of flaps or ears integral with the insole at the opposite shank edges thereof which are bent upwardly to cover the upwardly bent portions of the underlying arch support. With this construction it is difficult to secure a flat sock lining in place upon the insole.

The principal object of the present invention is to produce a machine by which a sole-shaped shoe part, the sock lining for instance, may be shaped to fit the underlying shoe structure when applied thereto.

To the accomplishment of this object, and such others as may appear, the various features of the present invention relate to certain devices, combinations and arrangements of parts described hereinafter and then set forth broadly and in detail in the appended claims.

The various features of the present invention will be readily understood from an inspection of the accompanying drawings illustrating the best form of the invention at present known to the inventor, in which,

Figure 1 is a view in front elevation;

Fig. 2 is a view in plan;

Fig. 3 is a view in right side elevation;

Fig. 4 is a detail view, partly in section, showing the relationship of the parts which cooperate to shape the work.

Fig. 5 is a view in perspective of the clamp for clamping the shoe part upon the work support;

Fig. 6 is a view in perspective of the work support, and

Fig. 7 is a view in perspective of a shaped sock lining.

In the illustrated embodiment of the invention the sole-shaped sock lining is supported flatwise upon a work support having a planar work supporting surface comprising a rubber bed 8, (Fig. 6), secured, with its edges flush, to a plate 9. The sock lining is supported finished face down upon the bed 8, the toe and heel portions of

the sock lining engaging the broad ends of the bed, respectively. As illustrated in Fig. 6 the toe and heel supporting portions of the work support are connected by a narrow web arranged in the median line of the work support, the lateral edges 5 faces of this web being curved concavely. With this construction, the marginal shank portions of the sock lining overlap lateral blind concave edges 10 and 11 in the work support.

The plate 9 is carried by a pair of vertical 10 stilts 13 (Fig. 1) formed on one end of a bracket 14, (Fig. 3), which is bolted at its other end to a cross brace 15 of the machine frame. The frame is provided with bosses 16 and 17, (Fig. 1), which receive, respectively, rods 18 and 19 the upper 15 and lower ends of which are tied together by upper and lower crossheads 20 and 21. The frame of the machine is carried by a triangular base 22, (Fig. 2), mounted upon three legs 23 which may be secured to the floor.

With this construction, the rods 18 and 19 are free to slide in the bosses 16 and 17, their downward movement being limited by the engagement of the crosshead 20 with the upper bosses and their upward movement being limited by the engagement of the crosshead 21 with the lower bosses.

In order to clamp the sock lining upon the work support, a bracket 24, (Fig. 3), projecting forwardly from the crosshead 20, loosely carries 30 two depending rods 25, (Fig. 1), to the lower ends of which is secured a clamp 26 having the same shape as the bed 8. The work engaging face of the clamp 26 comprises a flexible sheet of rubber 27, (Fig. 5), the ends of which are clamped between the upper surface of the clamp 26 and a pair of bars 28 secured thereto. As shown in Fig. 5, the lateral sides of the rubber sheet are parallel and overlie the concave edges 10 and 11 in the bed 8.

The downward movement of the clamp 26 is limited by adjusting nuts 29 carried by the upper ends of the rods 25 and arranged to engage the bracket 24. Coiled about each rod 25 and interposed between the upper surface of the clamp 26 and the bottom of the bracket 24 is a spring 45 35 40 45 30.

To lower the clamp 26 upon the work, the crosshead 21 is connected through a treadle rod 31 to a treadle (not shown) the usual coiled spring 50 being provided to elevate the crosshead 21 and its associated parts when the treadle is released. With this construction, depression of the treadle lowers the clamp upon the work support, the stroke of the crosshead 20 being greater than the 55

clamp to cause the springs 30 to be compressed and thus cause the clamp to exert an efficient clamping pressure upon the work.

In order to shape the portions of the shoe part overlying the concave edges 10 and 11, the bracket 24 carries a shaping tool, herein shown as formed in two parts 32 and 33, both being fungiform. As shown in Fig. 3 the bracket 24 is provided with two oppositely disposed hubs 34 and 35 in each of which a rod 36 is loosely mounted. One end of the rod 36 is threaded into a stem 37 projecting from the concave surface of a head 38, the convex surface of which is substantially the surface of a hemisphere and terminates in a circular edge 39. The two heads 38 are pressed towards each other by springs 40, each being coiled about the rod 36 and stem 37 and interposed between the adjacent hub and the convex surface of the head, there being a combined adjusting and clamping nut 42 on the free end of each stem to limit the movements of the heads towards each other.

As shown in Fig. 3, the stems 37 of the fungiform shaping tools 32 and 33 are arranged in a plane parallel to the work supporting surface of the work support and normal to a plane intersecting the median line of the work support. The circular edges 39 of the fungiform shaping tools are arranged in a plane parallel to the plane intersecting the median line of the work support. The heads 38 of the fungiform shaping tools are interposed between the last two named planes.

With this construction and arrangement, depression of the treadle first lowers the clamp to clamp the work upon the work support and then causes the fungiform shaping tools to pass by the concave edges 10 and 11. During this movement the lower portion of the heads 38 engage the portion of the rubber sheet 27. As the movement continues the heads wipe the work underlying the sheet about the curved edges 10 and 11. As the heads 38 approach the position of Fig. 4 the pressure of the shaping operation causes the heads 38 to move away from each other thus compressing the springs 40 which exert a heavy pressure on the bent work interposed between the heads 38 and the curved edges 10 and 11. Thus, during the shaping operation the shaping tool and the work support are moved relatively in two directions normal to each other.

What is claimed as new, is:

1. A machine for shaping a sole-shaped shoe part having, in combination, a work support having a planar work supporting surface and a concave curvature along at least a portion of at least one of its lateral edge faces, said curvature to be overlaid by the shoe part, a clamp for clamping the shoe part flatwise upon the work support, a fungiform shaping tool, and means for relatively moving the work support and the tool vertically to cause the head of the tool to bend that portion of the shoe part overlying the curvature about the curved edge thereof.

2. A machine for shaping a sole-shaped shoe part having, in combination, a work support having a planar work supporting surface and a concave curvature along at least a portion of at least one of its lateral edge faces, said curvature to be overlaid by the shoe part, a clamp for clamping the shoe part flatwise upon the work support, a fungiform shaping tool, and means for relatively moving the work support and the tool

vertically and laterally to cause the head of the tool to bend that portion of the shoe part overlying the curvature about the curved edge thereof and against the edge face thereof.

3. A machine for shaping a sole-shaped shoe part having, in combination, a planar work support having at least one concave edge face to be overlaid by the shoe part, a clamp for clamping the shoe part flatwise upon the work support, a fungiform shaping tool having its stem arranged in a plane parallel to the work supporting surface of the work support and normal to a plane intersecting the median line of the work support, its circular edge arranged in a plane parallel to the second-named plane, and its head interposed between the last two named planes, and means for relatively moving the work support and the tool vertically to cause the head of the tool to bend the overlapping portion of the shoe part about the concave edge face.

4. A machine for shaping a sole-shaped shoe part having, in combination, a work support having a planar work supporting surface and at least one concave edge face to be overlaid by the shoe part, a clamp for clamping the shoe part flatwise upon the work support, a fungiform shaping tool having its stem arranged in a plane parallel to the work supporting surface of the work support and normal to a plane intersecting the median line of the work support, its circular edge arranged in a plane parallel to the second-named plane, and its head interposed between the last two-named planes, and means for relatively moving the work support and the tool vertically and laterally to cause the head of the tool to bend the overlapping portion of the shoe part about the curved edge face and to press the bent portion of the shoe part against the curved edge face.

5. A machine for shaping a sole-shaped shoe part having, in combination, a work support having a planar work supporting surface and two concave edge faces, one at each side of the work support to be overlaid by the shoe part, a clamp for clamping the shoe part flatwise upon the work support, a shaping tool having two fungiform shaping parts, mounted to move towards each other yieldingly and to move away from each other under the pressure of the shaping operation and means for relatively moving the work support and the tool vertically to shape those portions of the shoe part overlying the concave edge faces.

6. A machine for shaping a sole-shaped shoe part having, in combination, a work support having a planar work supporting surface and concave lateral side edges, a clamp for clamping the shoe part flatwise upon the work support, and a shaping tool having two fungiform shaping parts to wipe the lateral sides of the shoe part downward about the concave lateral side edges of the work support, respectively.

7. In a machine for shaping a sole-shaped shoe part, the combination with a support and a shaping tool mounted thereon comprising two fungiform shaping parts each comprising a stem loosely carried by the support, a head mounted on the stem, a spring coiled about the stem and interposed between the support and the concave surface of the head, and means for limiting the movement of the stem under the influence of the spring.

WALTER P. OSGOOD.
